UNITED STATES PATENT OFFICE.

EGMONT MAX TORMIN, OF NEWTON CENTER, MASSACHUSETTS, ASSIGNOR TO HOLTZER-CABOT ELECTRIC COMPANY, OF BROOKLINE, MASSACHUSETTS.

DYNAMO.

1,108,086.

Specification of Letters Patent. Patented Aug. 18, 1914.

Application filed March 3, 1911. Serial No. 612,140.

To all whom it may concern:

Be it known that I, EGMONT M. TORMIN, a subject of the Emperor of Germany, and a resident of Newton Center, in the county 5 of Middlesex and State of Massachusetts, have invented a new and useful Improvement in Dynamos, of which the following is a specification.

My invention relates to dynamo electric 10 machines and its object is to produce a direct current machine that can be short-circuited with impunity, and to provide the various improvements hereinafter more fully set forth.

15 One embodiment of my machine is illustrated in the drawings which accompany and form a part of this specification.

In the drawings, Figure 1 is a diagram showing one arrangement of circuits that 20 may be employed in connection with my improved dynamo. Fig. 2 is a horizontal longitudinal section. Fig. 3 is a longitudinal vertical section taken on the line 3—3 of Fig. 2.

25 In the drawings selected for more fully disclosing my invention, 1 is a casing of aluminum or other suitable material. One end of the casing is provided with a cover plate 3. A cap 4 secured to said plate by 30 the screw 4' and the pin 4'', or in any other suitable manner, may be employed to complete the inclosure of the dynamo.

Cast integral with the plate is the housing 5 for the bearing 6, herein shown as a ball bearing. The casing is provided with a housing 7 for the other bearing 8, and the shaft 9 which carries the armature 10 and commutator 11 is arranged to rotate in the bearings 6, 8.

40 12 represents the laminated core of the field magnet consisting of very soft iron disks, which in the present instance are shown as riveted together by the rivets 12' and held in the casing by a driving fit. The 45 field core is provided with suitable windings, shown in the present instance as two series windings 14 and two shunt windings 13.

The forwardly-extending arms 17, 18, and the brush-holders 19, 19', each provided 50 with an integral flange 19'', are secured to the housing 5 and are suitably insulated from each other and from the other metallic parts of the machine.

The screws 20, 20' electrically and me-

chanically connect to the upper portion of 55 the arms 17, 18 the terminals 31, 31' which lead to the field windings and external circuit as shown in Fig. 1, the conductors which are connected to said terminals passing through the holes 34 in the cover plate. 60

The switch member 21, pivoted at 21' to the arm 17, carries the insulating plate 22 which is provided with the metallic button 23, and the end of said insulating plate projects through the bifurcated end of the arm 65 18 to connect with the spring 26 secured as shown to said arm 18. The contact points 24 on the switch and 25 on the arm 18 are normally separated by the head 27 cooperating with the button 23. The pin 27' 70 located in the bore at the forward end of the shaft 9 is normally held in the position shown in Fig. 1 by the arms 29' which are pivoted at 29' to the collar 28, the spring 30 secured to the governor weights 29 maintaining said pin in its outward position. 75 The leads 32 to the shunt windings 13 are electrically connected to the brushes.

Referring to the diagram shown in Fig. 1, the series windings 14 are connected 80 through armature 10 and the shunt windings 13 and thence by conductor 31 to the centrifugally-governed switch 21, and when the switch is closed, the storage battery 47, or other suitable source of energy, is connected in circuit through the conductor 31' 85 and the contact points 24, 25. The spring 30 of the governor is so adjusted that when the armature arrives at a predetermined speed of rotation, the head 27 is drawn inwardly by the action of the governor, and the contacts 24, 25 and 24', 25' closed by the action of the spring 26.

The shunt field coils are so designed and the laminated field core is so constructed and proportioned that the residual magnetism of the latter is insufficient at the maximum speed or rotation of the armature to excite said field coils to the degree necessary to enable the machine to "pick-up". It follows as a 100 matter of course that for any speed lower than said maximum speed, the machine will not "pick-up". It will be understood that by the term "maximum" speed, I mean the greatest speed at which the machine would 105 be likely to be driven in ordinary usage. When the machine is driven at speeds higher than that which I term the "maximum"

speed, the machine may or may not "pick-up", but it will be understood that such speeds are but rarely attained.

Inasmuch as the particular machine specifically described herein is designed for motor vehicles, it will be understood that its speed will vary between wide limits.

It is of course well understood that it is not new to provide direct current generators with laminated field cores and that such generators will "pick-up" at definite speeds, although at much lower speeds they will not "pick-up", but in the present invention the field coils are so designed and the laminated field core is so constructed and proportioned that for the highest speed at which the machine in ordinary usage is likely to be driven, the residual magnetism will not cause it to "pick up". As soon as a definite speed has been reached and the contacts at 24, 25 closed, the source of energy 47 is connected in circuit with the field windings and the machine at once proceeds to generate current. The direction of current flow from the source 47, which preferably is a storage battery of the Edison type (nickel hydrate and iron oxid plates in a potassium hydrate bath) is shown by the solid arrows, and that of the current developed by the generator is shown by the dotted arrows. It will be noted that the direction of the flow of the two currents through the shunt coils is the same and that of the flow through the series coils is opposite. As soon as the coils are energized by the source 47, the potential developed by the generator exceeds that of said source and the current from the latter ceases to flow through the generator. Should the generator become short-circuited across the leads to the battery 47, it will be obvious that the excitation of the machine will drop to practically zero, and the electromotive force developed across the brushes will be negligible.

Inasmuch as there is not sufficient residual magnetism in the field to enable the machine to "pick-up", no precautions are necessary in connecting the battery to the dynamo. For example, in the present case the right hand brush is positive because it is connected to the positive pole of the battery, but if the battery were reversed, said right hand brush would become negative. In other words, the polarity of the source governs the polarity of the dynamo, because the voltage impressed by the armature at and below maximum speed on the field magnet, due to the residual magnetism of the field core is less than the voltage impressed upon said magnet by the battery.

Inasmuch as the Edison battery above re-

ferred to cannot be injured by overcharging or over-discharging, or complete exhaustion, battery protecting devices are not required.

48, 48' represent lamps connected in parallel with the external circuit of the generator and also with the storage battery 47. In an automobile they would represent, for example, the side lights. It will be understood, however, that my generator is not limited to use with motor vehicles. As soon as the speed of rotation falls below that which is necessary to close the contacts 24, 25, the external load, such as the lamps 48, 48' are supplied entirely by the source 47.

A convenient means of driving the generator when used on automobiles is shown in Fig. 2. The clutch members 40, faced with rawhide 41, or other suitable friction material, are slidably mounted on the shaft 9 and prevented from having rotational movement relative thereto by the spline 50. Each of the barrels 42 is provided with a plurality of pins 43 and spiral springs 44. One set of pins co-operates with the collar 39 and the other set with the collar 45, secured to the shaft by the cotter pin 46. The rim of the fly-wheel 49 of an engine may be held in frictional engagement with the clutch members, the degree of engagement there-with being determined by the springs 44.

It will be understood that while I have described one embodiment of my invention with some particularity, nevertheless various modifications may be made by those skilled in the art, both in the apparatus described and in the circuit arrangements employed therewith, without departing from the principle of my invention.

I claim:

A direct current dynamo electric machine having a field magnet provided with a laminated core so constructed and proportioned with respect to the field coil that at the maximum speed of rotation the residual magnetism of said core will be insufficient to cause said machine to "pick up," an armature, and a source of electrical energy electrically connected with the armature and field magnet, the voltage impressed by the armature at maximum speed on said field magnet due to the residual magnetism of the field core being less than the voltage impressed upon said field magnet by said source of electrical energy.

In testimony whereof, I have hereunto subscribed my name this 1st day of March, 1911.

EGMONT MAX TORMIN.
